UNITED STATES PATENT OFFICE.

STEPHEN J. RIELLY, OF COALINGA, CALIFORNIA.

ROD OR PIPE CLAMP.

1,088,182.

Specification of Letters Patent. Patented Feb. 24, 1914.

Application filed December 19, 1912. Serial No. 737,697.

To all whom it may concern:

Be it known that I, STEPHEN J. RIELLY, a citizen of the United States of America, residing at Coalinga, in the county of Fresno and State of California, have invented certain new and useful Improvements in Rod or Pipe Clamps, of which the following is a specification.

This invention relates to rod or pipe clamps, and its object is to provide an improved device of this character adapted to readily and securely clamp a section of rod, shafting or pipe.

It is frequently desired to remove pump rods or casings from a well, or to lower such rods and casings into a well, and the purpose of the herein-described pipe clamp is to grip and hold such rods and casings to prevent them from dropping into the well and for holding the lowermost rods and casings while the upper ones are being removed and repaired.

The clamp comprises only two pieces adapted to be readily adjusted about the object to be held in place; one that may be quickly and readily secured in position and removed, and one wherein the action of a single wedge member secures the clamp in place.

Though this device is adapted for use in many relations, it is particularly adapted for use with pump rods and casings.

Further objects and advantages of the invention will be set forth in the detailed description which now follows.

In the accompanying drawing Figure 1 is a side elevation looking to the right in Fig. 3. Fig. 2 is a corresponding view looking to the left in Fig. 3. Fig. 3 is a sectional view with the rod shown in elevation, and Fig. 4 is a detailed perspective view of a key hereinafter described.

Like numerals designate corresponding parts in all of the figures of the drawing.

Referring to the drawing, the numeral 5 designates the rod to be clamped. This rod enters a central toothed bore 7, of a body member 8. A radial opening 9 formed in said body member receives a key 10. This key is provided with a toothed channel 11, laterally extending webs or ribs 12 and webs or ribs 13, which are inclined outwardly with relation to the body portion of the key, and which are provided with flaring outer portions serving a purpose herein-after set forth. The webs 12 and 13 are

inclined with relation to the body of the key 10 and engage in correspondingly inclined recesses 14 and 15 of the body member, so that as the key is driven toward the left in Fig. 3, it is, by reason of the inclination of the webs 12 and 13, caused to bear with great pressure upon the rod 5 and consequently to draw the body portion 8 toward itself. This causes the toothed bore of the body portion to grip the rod with great force. To prevent spreading of the body portion under the action of the wedge, the otherwise free portions 16 thereof are tied together by the flaring shape of the webs 13, the flaring terminal portions of said webs engaging behind the hook terminals 17 to prevent separation of the portions 16 with relation to each other, as will be readily understood.

From the foregoing description it will be seen that the present invention comprises efficient means for quickly grasping the body of a rod or pipe, and while it is particularly intended for use in connection with pump rods, and casings, it is apparent that it is capable of use in many other relations.

Having described my invention, what I claim is:

1. In a device of the character described, the combination with a body portion having a bore extending therethrough and having a radial opening to communicate with said bore, there being passages having inclined wedge walls formed in the side walls of said radial opening in combination with a key adapted to enter said radial opening, said key having wedge webs extending laterally therefrom which enter said passages, said key having its inner face complementally formed with relation to said bore, additional webs carried by said key, said webs having flaring terminal portions, there being correspondingly shaped recesses formed in the side walls of said radial opening in which said flaring webs engage, as and for the purposes set forth.

2. In a device of the character described, the combination with a body portion having a circular bore extending therethrough and having a radial slot of a width substantially equal to the diameter of said bore, a radially disposed key having its inner face complementally formed with relation to said bore, a pair of transversely extending wedge webs located at the inner terminal

portion of said key, and inclined with relation to the longitudinal axis of said bore, the side walls of the radial slot of the body portion having inclined passages formed therein in which said wedge webs engage, and a pair of additional webs projecting from the side faces of said key intermediate the first named webs and the outer end of said key, said last named webs being inclined with relation to the longitudinal axis of the bore and lying at an angle other than a right angle to the side faces of the key and having their outer terminal por-

tions flared to a greater thickness than the thickness of said webs at their point of juncture with said key, said side walls of the radial slot of the body portion having additional inclined passages formed therein in which said last named webs engage.

In testimony whereof I affix my signature 20 in presence of two witnesses.

STEPHEN J. RIELLY.
